UNITED STATES PATENT OFFICE.

SAMUEL LAWSON, OF NEW YORK, N. Y., ASSIGNOR TO HIMSELF AND ALONZO T. WELCH, OF SAME PLACE.

GAS-ENGINE.

SPECIFICATION forming part of Letters Patent No. 498,476, dated May 30, 1893.

Application filed October 2, 1891. Serial No. 407,499. (No model.)

To all whom it may concern:

Be it known that I, SAMUEL LAWSON, a citizen of the United States, residing in the city and State of New York, have invented an Improvement in Gas-Engines, of which the following is a specification.

In my patent, No. 462,492, granted November 3, 1891, I have represented a vertical igniting tube with a horizontal bend at the lower end opening into the valve case, and in the valve there is a notch or port through which the gases pass to the ignitor and the flame passes back through these parts to the cylinder.

In my present invention the igniting tube is attached to a moving valve, and in one position the valve opens into the port leading to the cylinder of the engine, for receiving the gases that are to be ignited; and in the other position of this valve an opening is provided to the external atmosphere, so that the confined gases within the igniting tube will escape to free such tube and prepare it for the reception of the gas to be ignited when the valve and igniting tube are moved to the port leading to the engine, and I give motion to the igniting tube and its valve by a connection to the main valve of the engine.

In the drawings Figure 1 is an elevation of the cylinder, valve case and ignitor, the heating tube or burner being removed. Fig. 2 is a section at the line x, x of Fig. 4. Fig. 3 is a sectional plan at the line y, y , Fig. 6. Fig. 4 is a sectional plan at the line z, z , Fig. 2. Fig. 5 is a sectional plan at the line z', z' , Fig. 1, and Fig. 6 is a vertical section at the line $x' x'$ of Fig. 3.

The cylinder A, piston C, piston rod D, port s, valve case L and valve b are similar to those in my aforesaid application, with the exception that the valve b is a plain cylinder without any notch or port. This valve b receives its motion from a connecting rod I to a gear that is revolved once for each two revolutions of the crank shaft, as usual in engines of this character, and the atmosphere is admitted at the pipe 15, and gas is admitted from the pipe 16 by the valve 17 into the passage 18, such valve 17 being opened at the

proper time so that the air and gas pass together into the cylinder A through the valve case L and port s as the piston C is descending, and the ignition takes place immediately after the piston C reaches its extreme upward movement, so as to give an impetus to the main shaft and fly wheel, and the escape valve H is open during the second up stroke of the piston, and the parts are so timed that the valve b in the case L descends to open the port s as the piston C commences to descend, and the valve 17 opens to admit the gas; and the valve b rises sufficiently to close the port s when the piston C commences its up stroke, the gas valve 17 simultaneously closing.

In view of the foregoing general explanation, it will now only be necessary to describe the igniting apparatus to which my present invention especially relates.

The igniting tube O is kept at a sufficiently high temperature to ignite the gas within it, and for this purpose a gas cock 23, jet 20 and Bunsen burner P' are provided, there being openings at 22 for the admission of air to promote the combustion of the gas, and a case P around the tube O for confining the heat of the flame to such tube. This tube O has a bend near its lower end and it is attached to the valve E, which is supported in proper slides at one side of the valve case or at the connection between the valve case and the cylinder (through which the port s passes). This valve E may be guided by a dovetail bar 4 and groove, and the face of the valve rests against the portion L' of the valve case, and there is an opening or port 5 in the valve and a port 6 in the portion L' of the valve case, which port 6 opens into the port s to the cylinder A.

When the valve E and igniting tube O are raised to the port 6, the gas, which at this time is confined and under pressure in the cylinder A, passes through the ports 6 and 5 into the igniting tube O and it is instantly ignited, and the flame passes back into the cylinder A to explode the gas therein, and in consequence of the fresh explosive gases passing through the port 6, there are no gaseous

products of combustion near the ignitor tube to render the ignition unreliable.

When the valve E is drawn down so that the port 5 comes below the port 6, such port 5 comes into line with a small hole or port 7 which opens to the external atmosphere. This port is represented in Fig. 3, and the gases under pressure in the igniting tube O expand and escape into the atmosphere, so as to empty this tube as much as possible and prepare it for receiving the next inflow of gas when it is raised to the position indicated in Figs. 2 and 4.

Any suitable mechanism may be made use 15 of for raising and lowering this valve E at the proper time. I have represented an arm 8 as extending out from the valve b and passing through a slot in the valve case L, and this arm 8 has an eye at its outer end and moves 20 freely over a screw rod 9 that is connected at its upper end with the valve E, and it is provided with lock nuts at 10 and 11, and these are adjusted in such a manner that after the valve b has been raised sufficiently to close 25 the port s the arm 8 comes into contact with the lock nuts 10 and raises the valve E, and the port 5 opens into the port 6 the moment the piston C has passed its uppermost movement; hence the gases under pressure pass 30 instantly into the ignitor and the explosion takes place as aforesaid, and the valve E remains in this position, so as to give ample time for the ignition, and when the valve b has moved downwardly sufficiently for the 35 arm 8 to come in contact with the lock nuts 11, such arm moves the valve E, closing the port 6 and bringing the port 5 into line with with the hole or port 7, so that the gases escape freely from the igniting tube, and upon 40 the upward movement of the valve b it closes the port s at the proper time and then keeps on moving and the arm 8 acts upon the lock nuts 10 and the motions before described are repeated.

45 By this improvement the proper time is given for the ignition of the gases in the cylinder and also for the escape of the spent gas in the igniting tube, and the exact period when the ignition takes place can be adjusted with great ease and accuracy.

When the parts are timed so that the igniting tube remains open to the cylinder until the piston reaches the end of the stroke after the explosion, a minus pressure will exist in

the igniting tube and the vent hole may not 55 be required.

I claim as my invention—

1. The combination with the piston and cylinder in a gas engine of a main valve and means for moving the same, an igniting tube and its heater and a valve carrying the igniting tube, and a connection between the main valve and the igniting-tube-valve, whereby the latter receives its motion from the former near the terminations of the movements in opposite directions substantially as specified. 65

2. The combination in a gas engine, with the cylinder and gas valve, of an igniting tube, a valve with which such igniting tube is connected, a burner for heating the igniting tube, an arm connected with the main valve, a screw rod connected with the valve of the igniting tube and adjusting nuts for regulating the action of the arm upon the valve, substantially as set forth. 70

75 3. The combination with the piston, cylinder and main valve, in a gas engine, of an igniting tube, a valve with which the lower end of the igniting tube is permanently connected and through which the tube opens, a port leading to the engine cylinder, through which the air and gas pass to the igniting tube and are exploded, and a port opening to the atmosphere, and with which the igniting-tube-valve coincides when not coinciding 80 with the port leading to the engine cylinder and a connection between the main valve and the ignitor valve to move the latter substantially as specified. 85

4. The combination with the cylinder and piston in a gas engine, of a main valve, a valve case in which such valve slides, means for supplying air and gas to the valve case, a port leading to the cylinder, an igniting tube and a valve carrying the same and sliding on 90 the main valve case, there being a port in the valve and a lateral port opening into the main engine port, and means for giving to the igniting tube and its valve a movement in harmony with the main valve, substantially as 95 specified.

Signed by me this 29th day of September, 1891.

S. LAWSON.
